UNITED STATES PATENT OFFICE.

MATHIAS R. VIKLA, OF WESELY, MINNESOTA.

COCKEYE.

No. 924,859.

Specification of Letters Patent.

Patented June 15, 1909.

Application filed January 21, 1908. Serial No. 411,959.

To all whom it may concern:

Be it known that I, MATHIAS R. VIKLA, a citizen of the United States, residing at Wesely, in the county of Rice and State of Minnesota, have invented certain new and useful Improvements in Cockeyes, of which the following is a specification.

This invention relates to certain new and useful improvements in cockeyes.

10 The object of my invention is to provide a simple device by means of which a trace may be secured to a swingletree.

A further aim of my invention is to provide a cockeye which will be held in frictional 15 engagement with the swingletree hook.

Other objects and advantages will be apparent from the following description, and it will be understood that changes in the specific structure shown and described may 20 be made within the scope of the claim without departing from the spirit of my invention.

In the drawings forming a portion of this specification and in which like numerals of 25 reference indicate similar parts in the several views, Figure 1 is a top view of the present invention, Fig. 2 is a similar view showing parts removed to more clearly illustrate the invention, Fig. 3 is a horizontal sectional view on 30 the line 3—3 of Fig. 1.

In carrying out the object of my invention, I employ a metallic elongated housing, having two extending ears 15 and 16. The cockeye at the end opposite these ears 15 and 35 16, terminates in a rounded portion 25 containing the access opening 22, while extending from one of the ears 15 to the opposite ear 16 is the bolt 17 as shown in Fig. 2. Slidably held between the inner walls 23 of 40 this housing, is the latch plate 31 having the forwardly extending portion 27 which projects into the access opening 22, as shown in Fig. 2. Upon its rear this latch plate 26 is slotted so as to receive the arm 32 of the 45 spring 34, the remaining end 33 of which spring presses against the rear wall of the cockeye housing as shown. This arrangement insures the latch plate being normally forced into a forward position. Extending 50 from the ears 15 and 16 are the edge flanges 12 and 24. Within the housing is formed a suitable chamber 20.

Snugly held between the edge flanges 12 14 and 24 of the housing is a face plate 38. This face plate is provided with a number of 55 extending nibs 39 which are secured within suitable recesses of the housing. By this means the said plate is securely fastened to the cockeye housing.

As shown in Fig. 3, the bottom 21 of the 60 cockeye is provided with a slot 36 through which the pin 35 extends, which pin is secured to the latch plate 26 and has an operating button 37, as shown. By means of this operating stem, the latch plate is actuated.

The edges 23 of the latch plate 26 are grooved to snugly receive the ears, as shown in Fig. 2.

The operation of my device is very simple. 70 In securing the cockeye, the latch plate is withdrawn so as to uncover the access opening 22. The cockeye can then readily be secured upon the trace hook and on releasing the latch plate, this cockeye will be removable 75 held to the swingletree hook.

The device is neat in appearance, simple of construction and may be readily operated.

Having thus described my said invention, what I claim as new and desire to secure by 80 U. S. Letters Patent is:—

A cockeye, comprising a metallic housing, having an access opening at one end, and two extending ears at the opposite end, the housing having a suitable chamber formed therein, provided with border flanges, a bolt extending from one of said ears to the other, a latch plate slidably held within said housing and partly entering said access opening, a spring positioned within said housing to normally force said plate into said access opening, a face plate having projecting nibs clamped about said housing, and held between said edge flanges, said housing having a slot and an operating pin projecting from 90 said latch plate and through said slot, all arranged substantially as set forth.

In testimony whereof I affix my signature, in presence of two witnesses.

MATHIAS R. VIKLA.

Witnesses:

ALBERT H. VIKLA,
WENCHEL J. VIKLA.
